REFRIGERANTS AND REFRIGERATION PROCESSES

Winston H. Reed, Radford, Va., and William A. Pennington, Fayetteville, N. Y., assignors to Carrier Corporation, Syracuse, N. Y., a corporation of Delaware

No Drawing. Application February 24, 1949,
Serial No. 78,228

3 Claims. (Cl. 62—178)

1 This invention relates to the art of refrigeration.

The general object of the invention is to provide an improved system of refrigeration which will enable the production of greater refrigeration effect with existing equipment than is now obtained by dichlorodifluoromethane hereinafter called by its trade-name "F12."

Another object is to provide a refrigerant for use with a compressor serving a refrigeration system so that when said compressor is driven by a motor served by 50 cycle current, refrigeration effect will be produced substantially equivalent to that obtained by F12 in such system with the motor served by 60 cycle current.

A further object is to provide a refrigerant which will produce an evaporating temperature approximately 10° to 15° lower than that obtained from the use of F12 in the same refrigeration system operated at the same condensing temperature.

Another object is to provide a refrigerant which will increase the capacity of a given refrigeration system approximately 12% when employing driving elements of given size for the compressor of the system over that possible of attainment with the use of F12 in the same system.

The chief feature of the invention is the provision of a refrigerant which will produce a given amount of refrigeration effect in equipment of smaller size or capacity than has heretofore been possible of attainment with available refrigerants suitable for use with safety to occupants of areas served by such equipment.

Another feature of the invention is the provision of a refrigerant mixture adapted for use in equipment designed specifically for the chief component of the mixture which enables the equipment to provide substantially the same refrigeration capacity even when operated at a substantial decrease in the number of revolutions per minute.

The problem of obtaining a refrigerant with capacity greater than that of F12 (dichlorodifluoromethane) but less than that obtained with F22 (monochlorodifluoromethane) has presented an unanswered challenge to the refrigeration industry. Compressors driven by motors served with 60 cycle current become inadequate to produce desired refrigeration effect when employed in areas where only 50 cycle current is available. Similarly compressors large enough to produce satisfactory results under moderate load conditions are inadequate under peak load conditions; in such cases, too, such a refrigerant would en-

able a compressor to be used satisfactorily when no existing size designed for F12 would be adequate. While the need for such a refrigerant was obvious, a search of available compounds failed to disclose any which would present a solution to the problem. Such a new refrigerant must not only have a capacity greater than F12 but also have all the other essential characteristics, that is be non-inflammable, substantially non-toxic, non-explosive, non-corrosive of ordinary metals encountered in a refrigeration system, stable under desired operating conditions and possessing a suitable melting point.

We have found an azeotropic mixture composed of dichlorodifluoromethane and methyl chloride to be particularly advantageous for the purposes described above. This specific azeotropic mixture is adapted for use with equipment designed for the use of dichlorodifluoromethane when it is necessary to operate said equipment at a considerable reduction in speed and provides a material increase in refrigeration capacity at such reduction in speed. Dichlorodifluoromethane possesses a boiling point of -21.7° F. at atmospheric pressure while methyl chloride possesses a boiling point of -11.4° F. at atmospheric pressure. When these ingredients are mixed in an amount comprising approximately 78.5 parts by weight of dichlorodifluoromethane and approximately 21.5 parts by weight of methyl chloride an azeotropic mixture is formed having a constant boiling point of approximately 32° F. at 50 lbs. per square inch absolute pressure. Theoretically this would indicate a boiling point of approximately -26° F. at atmospheric pressure. The mixture, therefore, possesses a lower boiling point and, from the standpoint of economy, somewhat lower in cost than a refrigerant composed solely of dichlorodifluoromethane.

The use of such azeotropic mixture in refrigerating equipment designed to employ dichlorodifluoromethane increases the capacity of the equipment. For example, assume refrigerating equipment such as a compressor designed for use with dichlorodifluoromethane and for operation with 60 cycle current at 1750 R. P. M. is instead operated with 50 cycle current. Such operation reduces the speed of the compressor to approximately 1450 R. P. M. with an accompanying reduction in capacity. Substitution of the azeotropic mixture of our invention in such compressor in place of dichlorodifluoromethane provides a material increase in capacity. The refrigeration capacity obtained by means of the substituted refrigerant compares favorably with the ca-

pacity of the equipment when the compressor is operated at its standard or normal speed with dichlorodifluoromethane.

Such equipment may be designed for use at a condensing temperature of approximately 104° F. and at an evaporating temperature of 32° F. In operation the azeotropic mixture may be condensed at a condensing temperature of 104° F. then transferred to the evaporator or heat exchanger to be evaporated at a temperature of approximately 32° F. to provide the required heat transfer. The evaporated mixture is then compressed and again condensed. The concentration of the refrigerant remains the same as it is evaporated or vaporized, with each of the components remaining in the same ratio with respect to the other. Likewise, the components in the refrigerant remain in the same ratio during the compression and condensation stages. In other words, the concentration and boiling point of applicants' refrigerant remain constant at any given pressure encountered during the refrigeration cycle.

When the compressor of such equipment using this refrigerant was run only five-sixths as fast as against full speed when F12 was used, no substantial difference in capacity resulted. Thus the new refrigerant where used in a machine with 50 cycle current gives almost the same refrigeration capacity as F12 does in the same machine with 60 cycle current. In all tests the power required for a unit of refrigeration was practically the same.

For purposes of nomenclature the new refrigerant will be called a refrigaloy.

Applicants' refrigaloy is chemically stable, causes no appreciable corrosion in metals normally encountered in a refrigeration system and has failed to burn even when the refrigerant was preheated to some 300° F. It provides a constant temperature throughout for example the entire length of an evaporator coil forming part of the refrigeration system.

We claim:

1. A refrigerant for use in a compressor-condenser-expander refrigeration system consisting

of a mixture of dichlorodifluoromethane and methyl chloride having a pressure at a predetermined temperature greater than the pressure of either component at such temperature and containing approximately 78.5 parts by weight of dichlorodifluoromethane and approximately 21.5 parts by weight of methyl chloride.

2. In a refrigeration system, a refrigerant comprising a vapor and a liquid in equilibrium with one another, the composition of said vapor being the same as the composition of said liquid, said refrigerant consisting of an azeotropic mixture of dichlorodifluoromethane and methyl chloride having a boiling point of approximately 32° F. at 10 50 p. s. i. a. and containing approximately 78.5 parts by weight of dichlorodifluoromethane and approximately 21.5 parts by weight of methyl chloride.

3. A method of increasing the capacity of a 20 system for producing refrigeration effect consisting in introducing into a refrigeration system a refrigerant consisting of approximately 78.5 parts by weight of dichlorodifluoromethane having a boiling point of -21.7° F. at a predetermined 25 pressure and approximately 21.5 parts by weight of methyl chloride having a boiling point of -11.4° F. at said pressure, the refrigerant having a boiling point of approximately -26° F. at said pressure, evaporating the refrigerant at a different pressure, the concentration of the refrigerant remaining the same as it is vaporized with the components remaining in the same ratio with respect to each other, and then successively compressing and condensing the refrigerant.
